UNITED STATES PATENT OFFICE.

LOUIS MEYERS, OF BROOKLYN, NEW YORK.

LOCK.

1,411,220.

Specification of Letters Patent. Patented Mar. 28, 1922.

Application filed December 10, 1918. Serial No. 266,059.

To all whom it may concern:

Be it known that I, LOUIS MEYERS, a citizen of the United States of America, residing at Brooklyn, New York, have invented 5 new and useful Improvements in Locks, of which the following is a specification.

This invention relates to locks.

The object of the invention is to provide a lock which has a curved bolt which may 10 be rocked so as to engage or become disengaged from a keeper, having a curved opening therethrough, and arranged adjacent to the lock. A further object is to provide such a lock with means whereby it 15 may not be operated by a key from the outside if desired. A further object is to provide a construction which will cooperate with the common form of barrel, such as is usually found in the type of locks known 20 as cylinder locks.

The invention consists of the construction, combination and arrangement of parts, as herein illustrated, described and claimed.

In the accompanying drawings, forming 25 part hereof, is illustrated a form of embodiment of the invention, in which drawings similar reference characters designate corresponding parts, and in which:

Figure 1 is an inside elevation, showing 30 the door and the door-jamb, the keeper being shown in section and the bolt of the lock retracted;

Figure 2 is an edge elevation of the door, showing the lock in end elevation;

Figure 3 is an outside elevation of the door, showing the projection, slotted end of 35 the lock casing;

Figure 4 is an elevation of the inside of the lock, a portion of the back cover being 40 removed;

Figure 5 is a vertical section taken approximately on the line 5—5 of Figure 1, looking towards the left hand;

Figure 6 is a vertical section taken approximately on the line 5—5 of Figure 1, looking towards the left hand, the parts being arranged in this figure so that the bolt of the lock will not be operated by a key inserted in the barrel; and,

Figure 7 is an elevation of one end of the lock casing, showing the means for preventing the bolt being operated by a key, such means being shown in operative position.

Referring to the drawings, 55 1 designates the door into which is set

the usual form of barrel 2, which barrel may be of the usual cylinder type and contain mechanism operated by a key so that the squared spindle 3 of the barrel may be 60 turned by the operation of the key. All of this mechanism is of the well-known type and is not claimed as a part of this invention, except in so far as a patentable combination may exist between it and the following described construction.

Secured on the door 1, on its inside face, is a casing 4, having a back cover 5 removably held in position by means of screws 6 and also provided with a slotted end 7, which 70 projects beyond the edge of the door 1 and is adapted to receive the keeper hereinafter described when the door is closed.

Disposed in the casing 4 is a segmental gear 8 having a curved, projecting portion 75 9 which forms the bolt of the lock. The segmental gear is arranged to rotate on a pin 10 extending transversely of the casing 4. A pinion 11 is disposed in the casing and arranged to mesh with the gear 8, and is 80 mounted on a sleeve 12 which projects through one wall of the casing 4 and terminates in a knob 13, provided with a shoulder 14. A spring 15 is disposed around the sleeve 12 so that one of its ends bears against 85 the pinion 11 and its opposite end bears against an adjacent portion of the wall of the casing 4, so that the pinion and knob are normally maintained in the position shown in Figure 5, that is to say, in the position 90 whereby the bolt may be retracted by the use of a key.

A sleeve 16 is provided with a squared bore and arranged to receive the squared spindle 3 and, as by means of a washer or 95 turned over end 17, is maintained on the back cover 5 so that it is free to rotate with relation to the casing. The sleeve 16 is of slightly less diameter than the sleeve 12, so that the sleeve 12 may slide longitudinally 100 thereof freely.

Disposed on the sleeve 16 and fixed thereto is a washer 18, provided with a lug 19 arranged in the path of movement of the pinion 11 and so arranged as to engage into 105 an opening 20 formed in one face of the pinion, when the pinion is forced to the position shown in Figure 5.

A pivoted finger 21 is disposed on the outer wall of the casing 4 and is arranged 110 to be rocked to the position shown in Figure 6 in order to hold the parts in the extended

position shown therein. A lug 22 maintains the pivoted finger 21 from swinging entirely around when the finger 21 is thrown to the position shown in Figure 1 5 of the drawings.

10 A keeper 23 is provided with a curved opening 24 and is arranged adjacent the door 1, so that when the door is closed the keeper will lie within the slotted end 7 of the casing 4. The keeper 23 may be maintained in position by any suitable mechanical means, such as the plate 25, screws 26, and a through bolt 27, fixed to the jamb 28 adjacent the door.

15 In the operation of the device, a suitable key being inserted in the barrel 2, the squared spindle 3 thereof may be rotated. With the parts in the position shown in Figure 6, the sleeve 16 will be rotated without rotating the pinion 11, because the lug 19 is then disengaged from the opening 20 of the pinion. The parts being in the position shown in Figure 5, under the tension 20 of the spring 15, the pinion 11 is forced to the right hand and the lug 19 engages in the opening 20 of the pinion so that rotation of the squared spindle 3 causes 25 rotation of the pinion 11. From inspection of Figure 4, it will be apparent that rotation of the pinion 11 will cause rotation of 30 the gear 8 on its pivot 10, so that the projecting end 9 of the segmental gear 8 would pass through the opening 24 of the keeper 23.

35 Having thus fully described the invention, what is claimed as new and desired to be secured by Letters Patent is:

1. A lock comprising the combination of 40 a key operated rotatable squared spindle, a rotatable sleeve provided with a squared bore arranged to receive the spindle, a second sleeve slidably disposed on the first sleeve, means for normally maintaining the two sleeves locked together, a bolt ar- 45 ranged to be rotated by rotation of one of the sleeves, and means for maintaining the two sleeves in unlocked position to permit the rotation of one sleeve without move- 50 ment of the bolt.

55 2. A lock comprising the combination of a key operated rotatable squared spindle, a sleeve provided with a squared bore into which the spindle is set, a washer secured on the sleeve and provided with a lug, a pinion slidably disposed on the sleeve and provided with an opening arranged to receive the lug, means for moving the pinion

longitudinally of the sleeve, and a rotatable bolt arranged to be operated by the pinion.

3. A lock comprising the combination of 60 a key operated rotatable squared spindle, a sleeve provided with a bore coincident with the spindle and into which the spindle is set, a washer secured on the sleeve and provided with a lug, a pinion slidably disposed on the sleeve and provided with an opening arranged to receive the lug, means for moving the pinion longitudinally of the sleeve, means for normally maintaining the lug in the opening in the pinion, and a 65 rotatable bolt arranged to be operated by the pinion.

4. A lock comprising the combination of 70 a key operated rotatable squared spindle, a sleeve provided with a squared bore into which the spindle is set, a washer secured on the sleeve and provided with a lug, a pinion slidably disposed on the sleeve and provided with an opening arranged to receive the lug, means for moving the pinion 75 longitudinally of the sleeve, means for maintaining the lug out of engagement in the opening, and a rotatable bolt arranged to be operated by the pinion.

5. A lock comprising the combination of 80 a key operated rotatable squared spindle, a sleeve provided with a squared bore into which the spindle is set, a washer secured on the sleeve and provided with a lug, a pinion slidably disposed on the sleeve and 85 provided with an opening arranged to receive the lug, means for moving the pinion longitudinally of the sleeve, a spring disposed around the sleeve and arranged normally to maintain the lug in the opening, 90 and a rotatable bolt arranged to be operated by the pinion.

6. A lock comprising the combination of 95 a key operated rotatable squared spindle, a sleeve provided with a squared bore into 100 which the spindle is set, a washer secured on the sleeve and provided with a lug, a pinion slidably disposed on the sleeve and provided with an opening arranged to receive the lug, means for moving the pinion 105 longitudinally of the sleeve, a pivoted member arranged to engage the pinion moving means to maintain the lug out of engagement with the pinion, and a rotatable bolt arranged to be operated by the pinion.

110 In testimony whereof I have signed my name to this specification.

LOUIS MEYERS.
